UNITED STATES PATENT OFFICE

ALEXANDER BOYNTON, OF SAN ANTONIO, TEXAS

AUTOMATIC WELL FLOWING DEVICE

Application filed November 11, 1927. Serial No. 232,656.

This invention relates to automatic well flowing apparatus, such as disclosed in co-pending patent applications filed April 5, 1927, No. 181,144 and filed May 17, 1927, No. 192,049, and it consists in the constructions, combinations and arrangements herein described and claimed.

An object of my present invention is to provide a differential pressure actuated valve whereby a maximum volume of pressure fluid is admitted to the liquid column when the apparatus is operating at a low differential pressure and gradually causes a reduction of the volume of fluid admitted to the liquid elevating conduit as the differential pressure increases.

Further the invention contemplates a differential pressure actuated valve apparatus embodying a plurality of passages which are successively restricted to permit a predetermined gradually decreasing volume of pressure fluid to pass to the liquid elevating conduit before the valve element finally closes or seals off.

With the preceding and other objects and advantages in mind the invention consists in the combination of elements, constructions and arrangement of parts and operations to be hereinafter specifically referred to, claimed and illustrated in the accompanying drawing, wherein

Figure 1 is a longitudinal sectional view of the flowing apparatus the valve plunger being in the open position,

Figure 2 is a fragmentary sectional view showing the valve plunger in the closed position,

Figure 3 is a perspective view of the plunger end guide this being one of the elements embodied in the invention, and

Figure 4 is a perspective of the plunger or valve element.

Referring to the invention in detail a valve body 5 for threaded connection with the adjacent ends of the well tubing sections 6 is provided. A longitudinally extending bore or valve chamber 7 is provided in an enlargement of the valve body 5 this chamber having a reduced area 8 which communicates with the conduit of the valve body 5 by way

of a transverse fluid pressure outlet port 9 and is formed with a valve seat 10 below this port.

Secured within the bore at predetermined points therein is a plurality of rings or annuli 11 which are pressed or otherwise provided within the bore. These rings are of the same diameter, but excepting the uppermost are graduated in length. That is, the rings gradually decrease in length beginning with the lower one, while the uppermost ring is of the same length as the ring next below. As a practical illustration the lower ring may be three-eighths inch long, the second five-sixteenths, the third one quarter and the fourth or upper ring one quarter. These rings constitute a plurality of communicating passages.

Co-operating with the rings or annuli in regulating the flow of fluid pressure through the bore is a cylindrical plunger 12 which is movable centrally through the rings or annuli and terminates in a stem 13 at its upper end which projects through the reduced area 8 of the bore. A plurality of circular heads 14 graduated in diameter are formed on the plunger at such predetermined intervals as to successively enter the rings or annuli and remain within the latter until the head next in order above occupies a position within its corresponding ring.

The difference between the diameter of upper plunger enlargement 14 and opening through bushing 11 should be .005". The difference between the diameter of the next lower plunger enlargement, also numbered 14, and the next bushing, also numbered 11, should be .010". The difference between the next lower plunger enlargement and bushing should be .015". The difference in diameter between the bottom plunger enlargement and the bottom bushing should be .020". All these dimensions may vary .002" or .003" either larger or smaller.

These heads are of the same length as their corresponding annuli, while the uppermost head constitutes a valve element 15 having a bevelled face 16 to seat upon the seat 10 to seal the bore when the differential pressure is sufficient. It is to be observed that the

circular heads or plunger enlargements 14 are provided with bevelled or tapering ends 14^a.

A bushing 17 is threaded in the lower 5 end of the bore and receives the lower end 18 of the plunger, the latter having spiral wings 19 which contact with the bore of the bushing to hold the lower end of the plunger in a co-axial position within the bore or 10 valve chamber.

A convex thimble 20 having an enlarged base 21 is arranged in the bore 7 above the port 9 and has a central guide bore 22 which receives and guides the upper end of the 15 stem 13 and co-acts with the bushing 17 in keeping the plunger in a co-axial position with respect to the walls of the bore so that the heads 14 will at all times be in proper relation to the rings or annuli.

20 For the purpose of resisting the effort of the plunger to rise so that the valve element will engage the seat 10 and seal off at a pre-determined differential pressure an expandable coil spring 23 is arranged in the upper 25 end of the bore with one end encircling the thimble and bearing against its base and its other end abutting a plug 24 threaded in the upper end of its bore.

Length of the coil spring should be 5" to 30 6", wrapped four to six coils to the inch. The diameter of the spring coil should be from $\frac{5}{8}$ " to $\frac{7}{8}$ ". The distance of the spring compression should be from $\frac{1}{2}$ " to 1".

The devices should be so spaced in the tubing string that the weight of fluid in the tubing between adjacent devices is from one-fourth to one-half as much as the pressure per square inch required to compress the spring and thereby force the plunger to sealing-off 35 engagement upon its upper seat. For illustration, assume the weight of the fluid between any two adjacent devices to be 30 lbs. per square inch, then the pressure per square 40 inch required to compress the spring and seal-off the plunger upon its upper seat should be 60 lbs. to 120 lbs.

The above spacing gives the best results and states the spacing rule correctly, but flow will be initiated and maintained if the 50 weight of the fluid per square inch between the valves is only slightly less than the pressure per square inch required to compress the spring sufficiently to cause the plunger to seal-off upon its upper seat. For illustration, assume the weight of the fluid between any two adjacent devices to be 30 lbs. per square inch, then the pressure per square 55 inch required to compress the spring until the plunger seals-off upon its upper seat must be slightly over 30 lbs. and should, as first stated, be from 60 lbs. to 120 lbs.

The operation may be readily understood. When there is no pressure acting upon the plunger it rests upon the bushing 17 with the 60 upper end of the stem spaced from the base

end of the bore 22. However, initial differential pressure raises the plunger a predetermined distance to engage the upper end of the stem with the thimble to place the coil spring under compression.

At this time the heads are in advance of 70 their respective rings or annuli and allow a maximum volume of pressure fluid to pass through the bore and into the conduit 5. As the differential pressure increases the heads 75 successively enter their respective rings or passages gradually or step by step restricting the flow of fluid through the rings or passages until the valve element finally engages the seat to seal the bore.

It has been pointed out that the plunger enlargements 14 are of successively graduated 80 diameters in the upward direction. The reader can readily conceive a modification where-in the enlargements are all of exactly the 85 same diameter while the bushings 11 may be made of different diameters. This arrangement will merely constitute an inversion of the arrangement disclosed in Figures 1 and 2. Exactly the same result will be obtained. 90 It is regarded unnecessary to illustrate the latter modification because the principle is readily understood from the description.

In either event the valve apparatus will 95 comprise a chamber provided with a plurality of restrictions in which chamber is operable a plunger or valve element having a plurality of enlarged sections. These enlarged sections co-act with the restricted sections afforded by the sleeves 11 in the valve chamber in such manner as to permit the flow of relatively large volumes of pressure fluid during periods of low pressure differentials. On the same principle the valve apparatus will permit the passage of a gradually decreasing 100 volume of pressure fluid during periods of relatively higher pressure differentials.

I claim:—

1. A valve comprising a body having a chamber, a plunger operable to effect a volumetric control of fluid flowing through the chamber, a spring capable of resisting the plunger, a stem on the plunger, and a thimble having a base upon which one end of the spring bears, and having a guide bore receiving the stem and in respect to which the stem and plunger have limited initial movement before the function of the spring is exercised.

2. A valve comprising a body having a chamber with a reduced area having a port, said area dividing the chamber into upper and lower portions, a plunger operable in the lower portion to effect a volumetric control of fluid flowing through said port, a stem on the plunger extending through said area to the upper portion, a spring situated in the upper portion capable of resisting the plunger and a thimble having an enlarged base receiving one end of the spring and being seated on the bottom of the upper portion, said

thimble having a guide bore receiving the stem and in respect to which the stem and plunger have limited initial movement before the spring is exercised.

3. A valve comprising a chamber having annuli of varying lengths, and a plunger operable in the chamber having heads of varying lengths and diameters, initially stationed at varying distances from the respective annuli when the plunger is quiescent.

4. A valve comprising a body, a chamber having annuli at separated points, and a plunger operable in the chamber and annuli for throttling a fluid flow having heads initially stationed at varying distances from the respective annuli when the plunger is quiescent.

5. A valve comprising a body having a chamber with annuli, and a plunger operable through the annuli having a plurality of heads initially stationed at successively different distances from certain edges of the annuli when the plunger is quiescent, said heads being bevelled at those ends that will 25 coact with said edges of the annuli.

6. A valve comprising a body having a bore, means forming a plurality of communicating passages, and a fluid pressure responsive plunger in the bore carrying a plurality of heads of graduated areas so spaced on the plunger as to successively enter the passages and restrict their normal volume as the plunger is moved in one direction.

7. A valve comprising a body having a bore, with an inlet and an outlet and a valve seat intermediate its ends and further provided with circular longitudinally aligned passages, a plunger shiftable in one direction in the bore by pressure fluid passing through the inlet, having a plurality of circular heads changing in position with respect to the passages to restrict the flow of pressure fluid therethrough incident to the movement of the plunger, and a valve element on the plunger to engage the valve seat after the plunger has been moved a predetermined distance.

8. A valve comprising a body having a bore, with an inlet and an outlet and a valve seat intermediate its ends and further provided with circular longitudinally aligned passages, a plunger shiftable in one direction in the bore by pressure fluid passing through the inlet, and having a plurality of circular heads of progressively graduated diameters successively entering the passages to restrict the flow of pressure fluid therethrough incident to the movement of the plunger, a valve element on the plunger to engage the valve seat after the plunger has been moved a predetermined distance, and a spring resisting the effort of the plunger to move in one direction.

9. A valve comprising a valve chamber, annuli disposed in the chamber, and a plunger movable through the annuli and having cylindrical heads of increasing areas to successively enter the annuli to restrict their 70 normal volume as the plunger moves therethrough.

10. A valve comprising a valve chamber, annuli of graduated lengths in the chamber, a plunger movable through the annuli and 75 having heads of gradually increasing areas along its length to successively enter the annuli to restrict their normal volume as the plunger moves therethrough.

11. A valve comprising a valve body having a passageway, a valve element operable in the passageway by the pressure of fluid flowing therein, and associated sets of cylindrical formations both upon the passageway and valve element, the effective diameters of one of the sets of formations varying 85 in progression from one end to the other of said passageway to provide variable effective passages for the throttling of the by-passing fluid.

Signed at San Antonio in the county of Bexar and State of Texas this 22d day of Oct. A. D. 1927.
